UNITED STATES PATENT OFFICE.

GEORGE SINON COLLINS, OF MEADVILLE, PENNSYLVANIA.

LOCK FOR PLUGS.

Application filed April 29, 1924. Serial No. 709,867.

To all whom it may concern:

Be it known that I, GEORGE S. COLLINS, a citizen of the United States, and a resident of Meadville, in the county of Crawford and State of Pennsylvania, have invented a new and Improved Lock for Plugs, of which the following is a full, clear, and exact description.

This invention has relation to locking devices and has particular reference to a locking device for plugs which are especially designed for use in connection with grease cups, although not necessarily restricted to such use.

The outstanding object of the present invention resides in the provision of an extremely simple and inexpensive form of locking means for positively precluding the retrograde or unthreading movement of a plug whereby loss or displacement of the same is eliminated.

As a further object the invention comprehends a plug locking means which is readily operable to lock or release the plug when necessary.

With the above recited and other objects in view, the invention resides in the novel construction set forth in the following specification, particularly pointed out in the appended claims and illustrated in the accompanying drawings, it being understood that the right is reserved to embodiments other than those actually illustrated herein to the full extent indicated by the general meaning of the terms in which the claim is expressed.

In the drawings—

Figure 1 is a side view of the plug removed from the container, receptacle or other member with which it is engageable.

Fig. 2 is a side view of the member with the plug removed.

Fig. 3 is a vertical sectional view with the plug in applied position to the member and with the locking means inserted.

Fig. 4 is a sectional plan view taken approximately on the line 4—4 of Fig. 3.

Referring to the drawings by characters of reference, 10 designates a plug which is provided with an externally threaded boss 11 adapted to screw into an internally threaded filling opening 12 of a receptacle, container or other member 13. In order to provide means for locking the plug against unthreading or retrograde movement when in applied position, the said plug is provided with an annular peripheral groove 14, while the neck 15 of the receptacle or container defining the outlet opening is provided with aligned apertures 16 in a plane which intersects the outlet opening and the groove 14 when the plug is in applied position. A retaining pin 17 is then inserted through the apertures 16 so that a portion of the pin intersects the groove and prevents removal thereof. The pin 17 may be in the nature of a cotter pin in which instance one extremity thereof is spread as at 18, or if desired a length of wire may be used in lieu of the pin, the opposite ends of which are bent to prevent its removal. Under this construction and arrangement it will be observed that the plug is effectually locked against displacement when the pin is in inserted relation. In order to remove the plug it is only necessary to withdraw the pin which admits of unthreading or retrograde movement of the plug to effect its removal.

I claim:

The combination with a member having a bossed outlet formed with an internally threaded portion constituting a seat and a closure plug having a threaded boss and a peripheral flange spaced from the threaded portion of the boss to define an annular groove, of means for locking the plug in closed relation to the bossed outlet comprising aligned aperture portions in the bossed outlet and a retaining pin insertable through said aperture portions and presenting a part of said retaining pin in intersecting relation to the grooved portion.

GEORGE SINON COLLINS.
